Wm. H. Mulligan

UNITED STATES PATENT OFFICE.

CHARLES C. INGRAHAM, OF MINNEAPOLIS, MINNESOTA, ASSIGNOR TO CARTER-MAYHEW MANUFACTURING CO., OF MINNEAPOLIS, MINNESOTA, A CORPORATION OF MINNESOTA.

DISK SEPARATOR.

Application filed June 7, 1926. Serial No. 114,094.

My invention relates to disk separators of the type known to the trade as the "Carter-Mayhew" disk separator, and which separator is disclosed and broadly claimed in 5 Letters Patent of the United States No. 1,364,247, of date January 4, 1921, entitled "Grain separator", and provides certain improvements therein whereby the efficiency of the machine is increased and the operation 10 of the machine generally improved.

In machines of the above character, grain is moved through a container and in the container are a plurality of pocketed separating disks secured to a common approximately 15 horizontal rotary shaft. The pockets in the disks are of such size and form that they will receive certain kinds of material, such as wheat, and will reject certain other kinds of material, such as oats. In the operation of 20 the commercial Carter-Mayhew separator, for the separation of wheat from oats, for example, the oats will be rejected by the pockets and the wheat will be picked up by the pockets, carried upward and, by centrifugal force and gravity, will be thrown 25 out of the pockets into a receiving hopper located at one side of the main container. Extending along the receiving hopper is a "repeat" or return trough, the main portion 30 of which is normally covered by a sectional deflecting board. Working in the repeat trough is a spiral conveyor that carries stock from the latter back into the receiving end of the main container. At a certain point 35 in the operation of the machine, the disks will begin to carry over some of the oats with the wheat and, at such point, the sections of the deflecting board will be turned into open position, so that the commingled 40 wheat and oats will be delivered into the repeat trough and from thence delivered back into the receiving end of the main container.

My present invention is directed particularly to improved means for delivering the 45 commingled stock from the repeat trough back into the container and for commingling the same with the main stock where the latter is delivered into the container.

In the accompanying drawings, which 50 illustrate the invention, like characters indicate like parts throughout the several views.

Referring to the drawings:

Fig. 1 is a view chiefly in side elevation, but with some parts broken away and with some parts sectioned, illustrating a disk separator of the Carter-Mayhew type, embodying the features of my present invention; and

Fig. 2 is a section taken on the line 2—2 of Fig. 1.

The main container 3 is a horizontally disposed drum-like structure provided with heads 4 and 5 and supported by legs 6. At its receiving end, the container 3 is provided with a lateral intake spout 7 shown as equipped with a flow-controlling gate 8 and at its delivery end with a discharge spout 9, the latter, as shown, being applied to and communicating with an opening in one side of the head 5. At one side, the container 3 opens into a receiving hopper 10, the upper portion of which extends the full length of said container and the bottom of which is contracted and terminates in a discharge opening 11. Extending the full length of the container 3 and partly within the hopper 10 is a repeat trough 12, the inner side of which joins the adjacent side of the container 3, forming therewith a quite sharp edge 13 that is located far above the bottom 70 of the container. As shown, the hopper 10 is provided with a hinged cover 14 and the repeat trough 12 is provided with a cover made up of hinged sections 15. The sections 15 normally rest on the edge 13 and 75 form a deflecting board that will carry wheat dropped thereon over the trough 12 and into the hopper 10.

Extended axially through the container 3 and journaled in suitable bearings on the 80 heads 4 and 5 thereof is a shaft 16 which, at one outer end, is shown as provided with a pulley 17 over which a power-driven belt may be run to rotate said shaft.

The pocketed separating disks are laterally spaced and carried by the common shaft 16. As shown, said disks 18 are of annular form and are provided with radial spokes 19 by which they are connected to the shaft 16. The pockets in the disks 18 are indicated by the numeral 20 and for the separation of wheat and oats, will be of such size and form that they will pick up and contain the wheat, but will reject the oats. The

disks will be rotated in the direction of the arrow marked thereon in Fig. 2. Secured to the shaft 16, at the receiving end of the machine and in line with the intake spout 7 is 5 an agitator, as shown, in the form of diametrically extended propeller-acting blades 21 that are beveled or obliquely set in a direction to force the commingled stock toward the first or adjacent separating disk.

10 Extended through the repeat trough 12 and journaled in suitable bearings in the ends thereof is a shaft 22 that is equipped with a spiral conveying flange 23. The shaft 22 is rotated in a direction reverse to 15 the direction of rotation of the shaft 16, but at a relatively low speed, and, as shown, this drive is accomplished by a sprocket chain 24 that runs over a sprocket 25 on the shaft 16 and over an intermediate 20 sprocket 25^a secured to a spur gear 26 that meshes with a spur gear 27 on the adjacent end of the shaft 22.

15 The spiral conveyor 23 is thus arranged so that it will feed the stock from the front 25 back toward the rear or receiving end of the container. In line with the agitator blades 21 and intake spout 7, the repeat trough 12 is terminated in an upwardly extended hood or inverted discharge spout 28, the open upper end of which is immediately above the edge 13. Within the hood or hooded portion 28, the spiral conveyor 23 is terminated and the shaft 22 is therein provided with radial blades or fans 29, 30 which, under rotation in the direction of the arrow marked adjacent thereto on Fig. 2, serve to elevate the returned stock or grain and to throw or crowd the same out through the spout 28 and back into the main 35 container 3.

40 The spiral conveyor 23 illustrated has a right-hand trend and, hence, should be rotated in the direction already described, but as is obvious, if it had a left-hand trend, 45 it would require rotation in a reverse direction from that described.

Summary of operation.

45 The commingled stock, assumed to be wheat and oats, will be delivered into the receiving end of the machine through the intake spout 7 and will be progressively and successively subjected to the action of the several pocketed separating disks. The advance flow of the stock will be chiefly 50 through the openings in the disks. Under rotation of the disks through the commingled mass, the wheat will be picked up by the pockets while the oats, because of their relatively great length, will be rejected, and the wheat lodged in the pockets will be carried by the disks upward and over toward the receiving hopper 10 and will be discharged from the pockets under 55 the combined action of centrifugal force

and gravity. The wheat thus discharged will be thrown outward of the edge 13 and onto the sections of the deflecting board 15 that are then turned down or to operative positions indicated by dotted lines in Fig. 7^a 2. The operative sections of the deflecting board, as is evident, carry the wheat over the repeat trough 12 and into the hopper 10.

At some point where most of the good wheat has been removed from the commingled stock, the disks will begin to pick up some oats, and at such point, the sections 75 15 of the deflecting board should be turned over and outward so as to uncover the repeat trough 12 and permit the commingled 80 wheat and oats to be then delivered into said repeat trough. The commingled stock thus delivered into the repeat trough will, by the spiral conveyor 23, be carried back toward the receiving end of the container 85 and into the hooded portion 28, where the accumulating stock will be acted upon by the elevating blades 29 and, by the latter, thrown and crowded upward through the spout 28 over the edge 13 and back into 90 the receiving end of the main container. The stock thus returned to the receiving end of the container will be acted upon by the oblique agitating blades 21 and will be thoroughly commingled with the inflowing 95 stock and therewith pressed toward the first separating disk.

95 The above is what is believed to be the preferred embodiment of the present invention, but it will be understood that various modifications thereof may be made, all within the scope of the invention herein disclosed and defined in the claims.

What I claim is:

1. In a separator of the kind described, 105 the combination with a container and a plurality of pocketed separating disks working therein, of a repeat trough at one side of said container arranged to receive commingled stock from certain of said disks, a conveyor working in said repeat trough, and means at the delivery end of said repeat trough for delivering the returned stock therefrom directly back into the receiving end of said container. 115

120 2. In a separator of the kind described, the combination with a container and a plurality of pocketed separating disks working therein, of a repeat trough at one side of said container arranged to receive commingled stock from certain of said disks, a conveyor working in said repeat trough, elevating means at the delivery end of said repeat trough for delivering the returned stock 125 therefrom directly back into the receiving end of said container, a receiving hopper extending along and spaced outward from said repeat trough, and a sectional deflecting board normally forming a cover for said repeat trough, the sections thereof being ad- 130

justable to vary the amount of stock that will be delivered into said hopper and into said repeat trough.

3. In a separator of the kind described, the combination with a container and a plurality of pocketed separating disks working therein, of a repeat trough at one side of said container connected thereto by an opening located above the bottoms of said container and trough, a spiral conveyor working in said repeat trough, and elevating blades on the delivery end of said conveyor, operative to elevate the returned stock and to deliver the same directly back into the receiving end of said container.

4. The structure defined in claim 3 in combination with means for rotating said disks and spiral conveyor, the latter at a higher speed than the former.

5. The structure defined in claim 3 in which said repeat trough, at its delivery end, has an inverted spout-like hood in line with the elevating blades on said conveyor.

6. The structure defined in claim 1 in combination with an agitator arranged to rotate with said disks and working at the receiving end of said container and operative on the stock returned to said container from said repeat trough.

7. The structure defined in claim 1 in combination with an agitator arranged to rotate with said disks and working at the receiving end of said container and operative on the stock returned to said container from said repeat trough, the said agitator compris-

ing propeller-acting blades arranged to crowd the stock toward the first or adjacent disk.

8. In a separator of the kind described, the combination with a container and pocketed separating disks working therein, of a propeller-acting agitator mounted to rotate with said disks at the receiving end of the container, said agitator being of substantially as great diameter as said disks.

9. In a separator of the kind described, the combination with a container and pocketed separating disks working therein, of a propeller-acting agitator mounted to rotate with said disks at the receiving end of the container, said container having an intake spout at its receiving end arranged to deliver the commingled stock primarily to said agitator, said agitator being of substantially as great diameter as said disks.

10. In a separator of the kind described, the combination with a container and pocketed separating disks working therein, of a propeller-acting agitator mounted to rotate with said disks at the receiving end of the container, a receiving hopper and a repeat trough located at one side of said container in position to receive stock therefrom, and a rotary spiral conveyor working in said repeat trough and provided at its delivery end with elevating blades arranged to deliver the return stock upward and back into the receiving end of said container.

In testimony whereof I affix my signature.

CHARLES C. INGRAHAM.
